CLAIM

The ornamental design for a filter element for high-pressure sprayers, as shown and described.

DESCRIPTION

FIG. 1 is a perspective view of a filter element for high-pressure sprayers showing my new design.

FIG. 2 is front view thereof;

FIG. 3 is a rear view thereof;

FIG. 4 is a side view thereof;

FIG. 5 is an opposite side view thereof;

FIG. 6 is a top plan view thereof; and,

FIG. 7 is a bottom plan view thereof.

The broken line(s) define the bounds of the claimed design and form no part thereof.

1 Claim, 2 Drawing Sheets
